(No Model.)

F. M. DAY.
WARP STOP MOTION MECHANISM FOR LOOMS.

No. 596,443.

Patented Dec. 28, 1897.

UNITED STATES PATENT OFFICE.

FLORENCE M. DAY, OF HOPEDALE, MASSACHUSETTS, ASSIGNOR TO THE DRAPER COMPANY, OF SAME PLACE AND PORTLAND, MAINE.

WARP-STOP-MOTION MECHANISM FOR LOOMS.

SPECIFICATION forming part of Letters Patent No. 596,443, dated December 28, 1897.

Application filed July 9, 1897. Serial No. 643,933. (No model.)

To all whom it may concern:

Be it known that I, FLORENCE M. DAY, of Hopedale, in the county of Worcester and State of Massachusetts, have invented an Improvement in Warp-Stop-Motion Mechanism for Looms, of which the following description, in connection with the accompanying drawings, is a specification, like letters on the drawings representing like parts.

10 This invention has for its object the production of stop-motion mechanism for looms operative upon the breakage or undue slackening of the warp-threads, the consequent movement into abnormal position of a detector holding or stopping the movement of a normally-vibrated coöperating feeler.

The subject-matter of this present invention relates more particularly to the mechanism for normally vibrating the feeler, said 20 mechanism being simple and direct-acting and bringing as little strain as possible on a detector when engaged by the feeler.

Figure 1 is a front elevation of a portion of a loom with my present invention applied thereto. Fig. 2 is a vertical sectional view thereof on the line xx , Fig. 1, looking toward the left. Fig. 3 is a detail view to the left of the line xx of the mechanism for vibrating the feeler and a portion of the releasing devices for the shipper-lever, the feeler being shown as having been stopped by a dropped detector. Fig. 4 is a detail of the segmental gearing for connecting the feeler rock-shafts, to be described; and Fig. 5 is an enlarged detail of a portion of the feeler in plan, a detector and its coöperating fixed abutment or stop being shown in section.

The lay and the harness-cams, harness-levers, and connections between them and the 40 harness-frames are omitted for the sake of clearness, such parts being old and forming no part of this invention.

The breast-beam A^0 , the harness cam-shaft C , the overhead connection between the harness-frames, and the shipper-lever S , held in the usual holding-plate S' against the stress of the actuating-spring S^X , may be and are of usual and well-known construction in looms.

Two series of warp-stop-motion-actuating 50 detectors $m m'$ are herein shown, serving also as heddles and slotted longitudinally to re-

ceive the supporting cross-bars $m^3 m^4$ at the top and bottom of the harness-frames, which latter are reciprocated in well-known manner, a separator-bar f being interposed between the lower ends of the detectors, serving as an abutment or stop for a dropped detector of either series when engaged by a feeler, the front bar f^X forming a warp-rest.

Two parallel rock-shafts $h h'$ are mounted in suitable bearings on stands H , one being shown in Fig. 1, and they are provided with arms h^X , to which are attached two oppositely-turned feelers $k k'$, vibratable in paths below and to coöperate with the detectors $m m'$,

respectively. The preferred form for the feelers is shown in Fig. 5, wherein the feeler k is shown as slotted transversely to form a series of tines k^X , having parallel sides and beveled points, the depth of the slots being equal to substantially one-half the width of a detector, such construction of the feeler, however, not being of my invention.

The shafts $h h'$ are connected, as shown, by segmental gears $g g'$, to thereby rock in unison in opposite directions to vibrate the feelers in the direction of the length of the warps, the shaft h' having fast thereon an arm h^2 , provided with a laterally-extended lug or projection h^3 , while the shaft h has fast thereon an arm h^4 , provided with a weight or enlargement h^5 , heavy enough to rock the shafts to move the feelers $k k'$ toward each other when unopposed.

The arms h^2 and h^4 are extended in opposite directions, each toward the rock-shaft to which the other is secured.

By means of the weighted arm h^4 and the connecting-gears $g g'$ the feelers are rocked by gravity in their vibratory movement toward the paths of the detectors.

An actuator to move the feelers in the opposite direction is shown as a longitudinally-movable bar N , forked at n to embrace the cam-shaft C , and provided with a suitable stud n' to engage the outer edge of a controlling-cam N^X on the shaft C , said cam moving between said stud n' and a toe n^X on the actuator N .

The actuator is slotted longitudinally at n^2 to receive a supporting and guiding stud

n^3 on a standard N^2 , fast on the loom-frame A, a second longitudinal slot n^4 at the upper end of the actuator receiving therein the laterally-extended lug h^3 of the arm h^2 .

5 The toe n^x and the weight of the actuator maintain the stud n' in engagement with the cam N^x and effect the release of the shipper-lever at the proper time.

On the actuator I have pivoted at d^x , near 10 its upper end, a dog d , provided with a tail d' , having a lateral lug d^2 to enter the slot n^4 , beneath the lug h^3 of the rocker-arm h^2 , a weight d^3 , as herein shown, tending to throw 15 the dog inward toward the actuator, the weight h^5 being much heavier than the weight d^3 .

A knock-off arm b , fast on a rock-shaft b^1 , is adapted to release the shipper-lever S from 20 its notch in the holding-plate, said shaft having a second arm b^2 , connected by a link b^3 with a rocker-arm b^4 , fast on a rock-shaft b^5 , mounted in suitable bearings on the cross-girth A¹⁵ and extended through a hole in the loom side.

The rock-shaft b^5 is provided with a second 25 arm b^6 , connected by a link b^7 with a bell-crank lever b^8 , loosely mounted on the cam-shaft C, adjacent the forked end n of the actuator N. Guides n^{10} of the latter receive a longitudinally-movable bunter t , preferably 30 notched at its upper end at t' to be engaged at times by the dog d , the bunter being pivotally connected at t^2 with the bell-crank lever b^8 .

When the bunter t is moved in the direction 35 of arrow 60, Fig. 1, the knock-off arm b will be operated, through the intervening connections, to release the shipper-lever and thereby effect stoppage of the loom. A pin n^{12} , extended across the space between the guides 40 n^{10} , prevents accidental withdrawal of the bunter from its said guides.

When the loom is running properly, the cam-shaft C, rotating in the direction of the arrows 22, Figs. 2 and 3, the actuator N will 45 be moved up, as in Figs. 1 and 2, by the cam N^x to swing the feelers outwardly, and then as the controlling-cam continues its rotation the actuator will be drawn down, permitting the weight h^5 to turn the rock-shafts by gravity 50 in the opposite direction to thereby move the feelers toward the detectors. The greater weight h^5 maintains the lug h^3 in engagement with the lug d^2 on the dog, causing the latter to rock on its fulcrum and throwing the dog 55 out beyond the notched end of the bunter as the dog is moved toward it by the downward movement of the actuator.

Should, however, a detector move into abnormal position, as shown at m' , Fig. 3, the inward movement of the feelers will be stopped and the lug h^3 will be held stationary at the time that the actuator begins its downward movement. The actuator as it moves downward carries the dog with it, the latter under 65 the influence of its weight d^3 swinging into position shown in Fig. 3 to engage the bunter, and such engagement with the bunter will

cause the latter to be moved with the actuator during the latter part of its downward stroke to thereby rock the bell-crank lever b^8 , 70 and through the intervening connections operate the knock-off arm b to release the shipper-lever.

The weight h^5 is only heavy enough to overcome the friction of the parts, and therefore 75 but little strain or pressure is brought upon a dropped detector by the construction herein shown.

The whole mechanism is at once simple, effective in operation, and not liable to derangement, and it will be noticed that I have done away with the use of springs altogether in the stop-motion mechanism.

Having fully described my invention, what I claim, and desire to secure by Letters Patent, is—

1. In a warp-stop-motion mechanism for looms, a series of warp-controlled actuating-detectors, a co-operating feeler moved by gravity toward and stopped by a dropped detector, a rocker-arm rigidly connected with the feeler, a reciprocating actuator to engage said arm and positively move the feeler in the opposite direction, a dog pivotally mounted on the actuator, and having a tail to be engaged by said rocker-arm, to normally retain the dog inoperative, combined with stopping mechanism for the loom, including a bunter adapted to be engaged and moved by bodily movement of the dog when in operative position on the actuator, stoppage of the feeler effecting movement through said rocker-arm of the dog into operative position, substantially as described.

2. In a warp-stop-motion mechanism for looms, including warp-controlled actuating-detectors, a plurality of independently-mounted vibratable feelers moved by gravity toward and to be stopped by a dropped detector, a reciprocating actuator to positively move the feelers in the opposite direction, connections between the feelers, to effect their movement in unison, a gravity-dog pivotally mounted on the actuator, and a detent controlled by movement of the feelers, to normally hold said dog inoperative, stoppage of a feeler releasing said dog and permitting it to move into operative position on the actuator, combined with stopping means for the loom including a bunter to be engaged and moved by the dog when in operative position, substantially as described.

3. In a warp-stop-motion mechanism for looms, a series of warp-controlled actuating-detectors, a co-operating feeler moved by gravity toward and stopped by a dropped detector, a longitudinally-reciprocating actuator, a dog pivotally mounted thereon, and a detent movable in unison with the feeler, to normally hold the dog inoperative on the gravity-actuated stroke of the feeler, said detent being engaged by the actuator to positively move the feeler in the opposite direction, combined with stopping mechanism for the loom,

including a bunter guided by and movable relatively to and adjacent said actuator, said bunter being in the path of the dog when in operative position due to stoppage of the 5 feeler, whereby the return stroke of the actuator will, through the dog mounted upon it, effect movement of the bunter and stoppage of the loom, substantially as described.

In testimony whereof I have signed my name to this specification in the presence of 10 two subscribing witnesses.

FLORENCE M. DAY.
